UNITED STATES PATENT OFFICE.

EDWARD DELOS COLE, OF MACON, ILLINOIS.

HAME-CLIP.

SPECIFICATION forming part of Letters Patent No. 296,530, dated April 8, 1884.

Application filed September 28, 1883. (No model.)

To all whom it may concern:

Be it known that I, EDWARD D. COLE, of Macon, in the county of Macon and State of Illinois, have invented a new and Improved 5 Hame-Clip, of which the following is a full, clear, and exact description.

The object of the invention is to improve hame-clips by means hereinafter described, and pointed out in the claims.

10 Reference is to be had to the accompanying drawings, forming part of this specification, in which similar letters of reference indicate corresponding parts in all the figures.

Figure 1 is a sectional plan view, showing 15 my new and improved hame-clip applied to the hame-tug. Fig. 2 is an edge view of the same; and Fig. 3 is a perspective view, showing the parts or sections of my new hame clip.

A represents the hame-tug; B, the hame-clip, consisting of the sections *a a*; and C represents the screw by which the sections *a a* are attached to the hame-tug A, and D, Fig. 1, represents the sleeve placed upon the screw C, for holding the rear ends of the sections *a* 25 *a* properly apart, and for forming a hinge-joint between the hame-tug A and clip B. The sections *a* of the clip B are duplicates of each other, and are each formed at the rear end with the eye *b*, through which the screw C passes, one of them being screw-threaded, to receive the screw-threaded end *c* of the screw C. In the center the sections *a* are formed with the inwardly-projecting plates *d*, that are adapted to abut against each other when the 35 clip is applied for use, as shown in Fig. 1, so as to brace and support and strengthen the sections *a* in the center. At the forward ends the sections *a* are turned to form the hooks *e*, which stand at right angles to the plane of the plates *d*, and these hooks, when the sections *a* 40 are put together, form the eye *h* of the clip, and the hooks *e* are correspondingly scarfed

off at one side in such manner as to form the diagonal or backwardly and outwardly inclined stop-shoulders *f*, against which the ends *e* of the hooks *e* fit, and the ends *e'* are made diagonal to correspond with the inclined shoulders *f*, so as to form a lock with them, to prevent the sections *a* from moving laterally upon each other, as will be understood from Fig. 2. 50

In applying the clip, the sections *a* are simply to be placed together, with the hooks *e* passing from opposite directions through the hame ring or staple, and then the rear ends of the sections are to be secured to the forward end 55 of the hame-tug A by the screw C, the screw passing through the sleeve D, placed in the fold of the leather forming the hame-tug, as clearly shown in Fig. 1. Constructed in this manner, it will be seen that by removing the 60 screw C the clip B may be detached from the hame, and also from the hame-tug, so that either may be changed in the harness, if desired, without destroying the hame-clip B. Besides this advantage, the clip is hinged upon 65 the screw C to the hame-tug, thus preventing the tug from bending and breaking at the connection; and, furthermore, the clip is cheap, practical, and durable, and easily applied.

Having thus described my invention, I claim 70 as new and desire to secure by Letters Patent—

1. The clip B, formed of the sections *a a*, in combination with the screw C and sleeve D, substantially as and for the purposes set forth.

2. The hame-clip B, composed of the hooked 75 sections *a a*, formed with the plates *d d*, shoulders *f f*, and diagonal ends *e e'*, in combination with the screw C and sleeve D, substantially as and for the purposes set forth.

EDWARD DELOS COLE.
